WILHELM SCHMITZ, OF BERLIN, GERMANY, ASSIGNOR TO VEREINIGTE EISENBAHN-SIGNALWERKE G. M. B. H., OF BERLIN-SIEMENSSTADT, GERMANY, A CORPORATION OF GERMANY

TRACK-SWITCH-CONTROLLING APPARATUS

Application filed April 5, 1929, Serial No 352,658, and in Germany June 8, 1928.

My invention relates to improvements in track switch controlling apparatus for railroad hump plants.

In automatic railroad hump plants the setting of the position of the track switches, hereinafter shortly called points, for individual cars released in succession is initiated in a special switch frame by the operator and the reversing of the points is afterward effected by the descending cars with the aid of rail contacts, insulated rails or the like. The function of the operator may consist either in the individual setting of the trips by means of manual keys or in the accumulation of a larger number of car journeys in magazine or accumulator devices specially designed for the purpose. Two different systems have been employed for this latter purpose. In one of the systems a special point magazine or accumulator is provided for each point, in which all the point settings necessary for the descending cars are accumulated prior to the commencement of the release of the cars. In the other system there is provided a trip magazine common to all points, in which the release of the cars is accumulated according to definite track routes and the points coordinated to each track are reversed with the aid of rows of running switches and with the cooperation of the train. This latter system has the advantage, that it is still possible to change the accumulation subsequently, in case the order relating to one or a plurality of cars has been changed. In the system with point operating magazines or accumulators it is necessary to equip all storage devices with as many switching positions as cars or groups of cars may pass across the respective point in the most unfavorable case.

The object of my invention is to produce by the combination of both systems a point setting controlling apparatus for a hump, which combines the advantages of both systems and eliminates their drawbacks.

This end in view is according to my invention attained by providing for each point a setting magazine, and besides a special trip magazine, in which the trips are stored up in advance, this magazine being controlled by

the descending cars transmitting the orders to the individual setting magazines. In the setting magazine of each point not the orders for all the cars are stored up, but only for those already descending and still located in front of the respective point. The control magazines may then be constructed considerably simpler and lighter. For the orders not yet stored up in the control magazine or accumulator an alteration is then easily possible in the trip magazine.

An embodiment of my invention is diagrammatically illustrated in the drawing affixed hereto and forming part of my specification.

Referring to this drawing, A is the trip or journey magazine or accumulator, which in known manner consists of a plurality of intersecting contact bars, the bars a, b, c, d and so on corresponding with the number of descending cars, which are to be accumulated in advance at the time, while the bars a₁, a₂, a₃, a₄ located at right angles to the bars a, b, c, d and so on are coordinated to the individual tracks g¹, g², g³, g⁴.

The crossing bars may, as shown in the diagram, be electrically connected by plug contacts b₁. Each of the bars a₁, a₂, a₃ and so on leads to one terminal of a solenoid switch 1, 2, 3, 4 and so on, the second terminal of which is connected to the source of current B by a common line C. Across the bars a, b, c, d and so on runs a contact lever sch₁, which is moved across the individual bars by means of a step switch magnet sch. Each time the electro-magnet sch attracts its armature a₆ the ratchet wheel a₇ is entrained by it and moves the contact lever sch₁, with which it is coupled, from one bar to the next.

In the position of the step switch contact sch₁ illustrated an impulse passes from the source of current across the magnet switch 2, bar a₂, contact b₁, bar a, step-switch contact sch₁, back to the source of current. In the control and lower portion of the drawing are shown the control circuits including the insulated rails at the track switches and the switch control electro-magnets s_{1a}, s_{1b}, s_{2a}, s_{2b}, and so on, which control the step switch solenoid sch. When a car travels over the

insulated rails $w1a$, $w1b$ the two switch magnets $s1a$ and $s1b$ receive current along the circuit D , $a8$, train axle E , $a9$ and $a10$, $s1a$ and $s1b$, $a11$, D and by attracting their armatures close the contacts $s1c$ and $s1d$ in the line to the step switch magnet sch .

The contacts $s1g$ and $s1h$ or $s2g$ and $s2h$ and so on are located at the control solenoids $s1a$, $s1b$ or $s2a$, $s2b$ and function in well known manner so, that when the first insulated rail, for instance $w1a$, is travelled over only $s1a$ receives current, and that then when both insulated rails $w1a$ and $w1b$ are occupied by train axles, both magnet switches are attracted and both contacts $s1g$ and $s1h$ are closed, so that now even if $w1a$ becomes free the magnet switch $s1a$ continues to receive current across the contacts $s1g$ and the insulated rail $w1b$ along the circuit: D , $a8$, train axle E , $w1b$, $a10$, $s1h$, $a38$, $s1g$, magnet winding $s1a$, $a11$, source of current D . Simultaneously a branch current flows from $a10$ across $s1b$, $a39$, all to the source of current D .

The track switches $w1$, $w2$, $w3$ are moved by driving motors $m1$, $m2$, $m3$. At the switch gear $m1$ the two field windings $e1$ and $e2$ provided for the movement of the switches to the left or right are connected across contacts $k1$ and $k3$ or $k2$ and $k4$ to the source of current. The contacts $k1$ and $k2$ are control switch contacts, which are in known manner moved by the track switch operating gear in such a manner, that in the minus position of the track switch the contact for the later plus position of said switch is closed. The contact $k3$ is mounted on the armature of the electromagnetic switch $w1c+$, the contact $k4$ at the electromagnetic switch $w1c-$. The supply of current to the electromagnetic switch $w1c-$ takes place across the line $a12$ and the contacts $1c$ or $2c$ at the track magnet switches 1, 2, line C , the source of current B and the contacts $s1e$ and $s1f$ at the armatures of the switch magnets $s1a$ and $s1b$.

In a similar manner current is supplied to the electromagnetic switch $w1c+$ across $a13$ and the contacts $3c$ or $4c$ at the track electromagnets 3 or 4, line C , source of current B , the contacts $s1e$ and $s1f$ at the armatures of the switch magnets $s1a$ and $s1b$. The electromagnetic switches $w1c+$ and $w1c-$ thus move the track switch into the plus or minus position by attracting their armatures. For the first car running down the incline the track switch is at once brought into the correct position. When adjusting the trip magazine for the second car the reversing of the track switch takes place as soon as the first car has completely traversed the insulated rails $w1a$ and $w1b$, because by the attraction of the electromagnets $s1a$ and $s1b$ during the occupation of the insulated rails $s1e$ and $s1d$ are closed. Step switch sch receives current and moves the contact lever $sch1$ onto the bar b by the operation of its armature; track

magnet switch 1 receives current and by attracting its armature closes the contact $1c$, which is connected in the circuit of $w1c-$. The switch solenoid $w1c-$ receives current if, and only if the contacts $s1c$ and $s1f$ connected in its circuit are closed, which, however, occurs only by the dropping off of the magnet switches $s1a$ and $s1b$. No special magazine is thus necessary at this track switch. For the remaining track switches $w2$ and $w3$ there are on the other hand provided switch magazines. Each switch magazine possesses three magnets. One of these prepares the reversal of the track switch into the plus or minus position. This is, for instance, in the case of the track switch $w2$ the electromagnetic switch $w2c-$. If $w2c-$ is traversed by current, it brings about the minus position, but if it remains dead the track switch is moved into the plus position, which is effected in the following manner: Every time its armature $a118$ is attracted $f2$ turns by means of the pawl $a119$ the ratchet wheel $a20$ forward by one tooth; $a20$ entrains the magazine drum $a21$ and the contact lever $a27$, whereby the pins $a22$ — $a25$ pass in succession past the magnet $w2c-$. If the armature has dropped off from $w2c-$, the pins remain in the position of the pins $a22$ and $a24$, but if the armature of $w2c-$ is attracted said pins are forced downward by the hammer $a26$, as shown, for instance, by the pins $a23$ and $a25$. The third magnet $t2$ is controlled across contacts $s2c$ and $s2d$ by the magnets $s2a$ and $s2b$, these magnets being connected to the insulated rails $w2a$ and $w2b$ of the track switch $w2$. The magnet $t2$ effects the release of the stored up orders when the insulated rails are traversed by the cars, in the following manner: the magnet $t2$ entrains, by means of its armature $a33$ and the pawl $a34$, the ratchet wheel $a35$, which in turn shifts contact lever $a27$ step by step in a circle below magazine drum $a21$, so that for each pull of magnet $t2$ the head of this lever passes in succession under one of the pins $a22$ — $a25$. The head of lever $a27$ remains vertically in the position shown, when it passes, for instance under the pin $a22$, but it is depressed when it comes under the pin $a23$. If it remains vertically in the position shown it closes across contact $p2+$, line $a28$, winding $e3$ (assuming that switch $V1$ is closed), motor $m2$, lines $a29$, $a30$ the circuit to the battery F , the second pole of which leads across lines $a14$ and $a31$ back to the contact $p2+$.

In the present case the plus position of the track point is already reached, so that the contact $p1$ is broken. If the lever $a27$ is, on the other hand pressed down, it closes the circuit across $p2-$, line $a32$, winding $e4$, $a29$, $a30$, battery F , $a14$, $a31$ to the contact $p2-$. In the first case the track switch is moved into the plus position, in the last case into the minus position. The pins are forced back

into the initial position by a stop located behind the lever $a27$ and not shown in the drawing. They are maintained in any position by a spring $a36$.

5 The minus position of the track switch is thus only brought about if one of the pins is pressed down by the electromagnet $w2c-$. The minus position of the track switch $w2$ is necessary for a journey to track $g1$. For 10 this track the bar $a1$ is provided in the switch magazine A across which the magnet switch 1 receives current and by attracting its armature closes the contact $1d$ in the line to the magnet $w2c-$. The plant functions in the 15 following manner:

Prior to the starting of the running down of the cars from the hump a cross-over track is coordinated to each car or each group of cars, in well known manner. For this purpose the contact 1 of the step switch magnet sch is connected with the bar a which in turn is connected by means of contact b to bar $a2$. Thereby the route for the first car, appertaining to bar a , to track g^2 is fixed. Magnet 20 switch 2 receives current by way of $+B$, C , 2 , $a2$, $b1$, a , $sch1$, $-B$. The magnet switch 2 is energized and closes its two contacts, whereby the switch magnet $w1c-$ receives current across $a12$ and contact $2c$, source of current 25 B and the contacts $s1e$ and $s1f$ at the dropped off magnet switches $s1a$ and $s1b$.

$w1c-$ closes the circuit across its armature contact $k4$, line $a14$, source of current F , $a15$, motor armature $m1$, winding $e2$, contact $k2$, 30 so that the motor rotates and throws the track switch $w1$ into the minus position. The second contact $2d$ of the magnet switch 2 supplies current to the switching magnet $f2$ of the switch magazine of the track switch 35 $w2$ along the circuit $2d$, $a16$, $f2$, $u2a$ at the dropped off armature of the magnet $u2$, line $a17$, $a18$, source of current B , and line C . By the attraction of $f2$ the track switch $w2$ is 40 thrown into the plus position in the manner described above. The track for the first car is thus simultaneously correctly set. If this car now runs down the incline and passes over the insulation of the first track switch, the 45 intermittent switch magnet sch receives current and moves its contact lever $sch1$ forward by one contact. In the trip magazine the circuit for the first car to track $g2$ is now cut off and that for the second car to track $g1$ connected up. By the deenergization of 50 relay 2, contact $2d$, located in the circuit of magnet $f2$ is opened, and $f2$ becomes deenergized and magnet switch 1 is energized by way of $+B$, C , 1 , $a1$, b , $sch1$, $-B$, attracts its armature and closes the contacts $1e$ and $1d$.

55 The switch magnet $w1c-$ receives current by way of $+B$, C , $1c$, $a12$, $w1c-$, $s1f$, $s1e$, $-B$. This maintains the minus position of the track switch $w1$. Switch magnets $w2c-$ and $f2$ receive current by way of: $+B$, C , $1d$, $u2-$, $f2$, $u2a$, $a18$, $-B$.

By magnet $w2c-$ receiving current, the minus position for track switch $w2$ is accumulated in the magazine $a21$, but track switch $w2$ is not yet thrown. This can occur only after the insulated rail portion $w2a$, 70 provided on the track switch, is traversed by the first car and has become again unoccupied. During this traversal switch magnets $s2a$ and $s2b$ receive current and close the contacts $s2c$ and $s2d$. Thereby switch magnet $t2$ receives current by way of $-B$, $a18$, $s2c$, $s2d$, $t2$, $+B$, and advances the magazine in the aforescribed manner with its contact lever $a27$ to the next pin, for instance $a23$. This pin is depressed by armature $a26$ so that 75 when this pin arrives above the contact lever $a27$, when drum $a21$ is revolved, lever $a27$ is depressed whereby contact $p2-$ is closed. By way of $p2-$ the winding $e4$ of the track switch motor $m2$ receives current in the following manner: current source F , $a14$, $a31$, $p2-$, $a32$, $e4$, $m2$, $a29$, $a30$, F . The track switch motor now commences to run and throws the switch points $w2$ into the minus 80 position.

Now it may happen that a route has been accumulated in the magazine, which is subsequently not to be used, perhaps because the pertaining car has in the meantime been misrouted or perhaps been previously assigned to another route. In this case—in order to avoid misrouting of all succeeding cars—the unused accumulated route must be artificially obliterated, i. e. the switching functions which otherwise the car in question would have performed must be carried out by hand. For this purpose a hand switch $h1$ is provided for each magazine, which, when depressed, for instance in the present example closes the circuit for the switch magnet $f2$ so that the latter advances the drum $a21$ one step.

The switch magnets sch , $f2$ and $f3$ ordinarily bring about the forward feeding of their pertaining step wheels $a7$, $a20$ when their respective armatures are attracted. It is more expedient, however, to perform this mechanical work not when an armature is attracted, but when it falls off, springs or other equivalent means, not shown here, being of course provided for pulling the armatures into the "off" position. If this mode of operation is to be attained, special switches $u1$, $u2$, $u3$ must be provided which are arranged in parallel to sch , $f2$ and $f3$, and thus obtain energizing current the same way as the latter. Their armatures control the current supply to sch , $f2$ and $f3$ respectively, so that when the armatures are attracted the current supply to sch , $f2$ and $f3$ respectively is interrupted so that when the armatures of the latter magnets drop off the mechanical feeding of the respective ratchet wheels is brought about. For instance when switch magnet $u1$ is energized its armature interrupts contacts $u1a$ through which magnet sch is supplied 115

with current and the latter magnet drops its armature a_6 and feeds ratchet wheel a_7 one step. At the same time armature a_6 interrupts the contacts sch_2 . In order to avoid the interruption of the energizing current for magnet u_1 when contacts sch_2 are opened, the armature of magnet u_1 when attracted immediately closes the two contacts u_1b , located in shunt to contacts sch_2 , whereby the current through magnet u_1 is maintained when magnet sch is deenergized. Magnets u_2 and u_3 are shunted in similar manner as will be noted from the drawings. The current through magnets u_1, u_2, u_3 is interrupted in the manner previously described, for instance in case of u_1 by the relay operated switches s_1c, s_1d .

The contacts h_1, h_2, h_3 are hand-operated as shown and serve the purpose of setting the track switches by hand as may be required at special occasions. If, for instance, switch h_1 is thrown to the left, the same circuits are established as if the magnet w_1c+ had been energized and contacts h_3 had been closed thereby. If hand switch is thrown to the right, the function of relay w_1c- is simulated, so that in the former case motor winding l_1 , in the latter case motor winding l_2 is energized and the track switch motor will set the track switch into the plus, respectively minus position. Hand levers h_2, h_3 function similarly. For instance, lever h_2 , when thrown to the left, substitutes the functions of contact p_2+ , when thrown to the right, it substitutes for contact p_2- . These independent hand operations may be required for instance in case a car has been routed the wrong way or if, after the magazine is already adjusted for the different routings, a car should be additionally routed to another track.

Various modifications and changes may be made without departing from the spirit and the scope of the invention, and I desire, therefore, that only such limitations shall be placed thereon as are imposed by the prior art.

I claim as my invention:

1. In an electric hump railway switching plant comprising a main track from which the cars of a train can be run automatically across a plurality of track switches on to branch tracks, in combination, a switch magazine for each track switch having means for storing route setting orders for the individual cars of a train to be decomposed, electric lines between the switch magazine and the coordinated track switches, means at the track switches operable by the cars and having means for advancing the switch magazine, a switching apparatus for receiving and transmitting the route orders for the individual cars to the switch magazine, and means located between said switching apparatus and said switch magazines for trans-

mitting the orders from said switching apparatus to said switch magazines.

2. In an electric hump railway switching plant comprising a main track from which the cars of a train can be run automatically across a plurality of track switches on to branch tracks, in combination, an electrically operated switch magazine for each track switch having means for storing route setting orders for the individual cars of a train to be decomposed, electric lines between the switch magazines and the coordinated track switches, insulated rails at the track switches for bringing about circuit connections through the car wheels to cause a forward motion of the switch magazine when said rails are traversed by the cars, a switching apparatus for receiving and transmitting the route orders for the individual cars to the switch magazine, and means located between said switching apparatus and said switch magazines for transmitting the orders from said switching apparatus to said switch magazines.

3. In an electric hump railway switching plant comprising a main track from which the cars of a train can be run automatically across a plurality of track switches on to branch tracks, in combination, an electrically operated switch magazine for each track switch having means for storing route setting orders for the individual cars of a train to be decomposed, electric lines between the switch magazines and the coordinated track switches, insulated rails at the track switches for bringing about circuit connections through the car wheels to cause a forward motion of the switch magazine when said rails are traversed by the cars, a common switch magazine for receiving and transmitting the route orders for all the tracks of said hump plant, means located between said common switch magazine and said insulated rails for transmitting an order contained in the common magazine to the individual magazines of the track switches when said insulated rails are traversed by the cars, and means located between the common magazine and the magazines of the track switches for transmitting the orders from the common magazine to the track switch magazines.

4. In an electric hump railway switching plant comprising a main track from which the cars of a train can be run automatically across a plurality of track switches on to branch tracks, in combination, an electrically operated switch magazine for each track switch having means for storing route setting orders for the individual cars of a train to be decomposed, electric lines between the switch magazines and the coordinated track switches, two insulated rails at each track switch, two relays connected with said insulated rails in such a manner that they receive current through said insulated rails

when traversed by the car, a common switch magazine for receiving and transmitting the route orders for all the tracks of the hump plant, contacts at the armatures of said relays, electric lines connecting said relay contacts with said common switch magazines and said track switch magazines, and relays located between said common magazine and the track switch magazines for transmitting the orders from said common magazine to said rail track magazines.

In testimony whereof I affix my signature.
